DISHWASHING APPARATUS

Clement Ehret, White Plains, N. Y.

Original application January 9, 1937, Serial No. 119,775. Divided and this application October 15, 1937, Serial No. 169,160

1 Claim. (CL 141—9)

This invention is a dishwashing machine, and while adapted for general use, is particularly intended for domestic purposes, being designed primarily for use in a home.

5 Domestic dishwashers are known to the art. In the majority of cases, they have been made as an independent piece of kitchen equipment. Most of them have been provided with their individual bases which take up considerable floor 10 space and are heavy and difficult to move about. Others have been formed integral with the sink, generally by forming the casing of the washer within the space normally occupied by the drain board. These constructions have not been entirely satisfactory. They are complicated, difficult to clean and expensive in their initial cost. If important parts become broken, repairs or replacements are difficult and in some instances the entire sink has to be replaced. Moreover, they 20 take up the space which the housewife ordinarily desires to use for other purposes and are not popular.

With the foregoing considerations in mind, the primary object of the present invention is to provide 25 a simple and efficient dishwasher, well adapted for domestic use and so constructed that it may be set into the sink like a large cooking kettle when it is desired to use the same and when not in use may be removed and stored in any 30 convenient or out of the way place.

The efficient washing of dishes requires that the same be accomplished by power driven mechanism, and another object of the invention is to provide a power driven dishwasher of this kind, 35 so constituted that it has, within this casing, a minimum number of working parts, so that it may be sufficiently light to be conveniently handled, but which working parts may be brought into cooperation with a power take-off permanently associated with a sink, thereby enabling the washer to be power driven when in actual use, but rendering it unnecessary for the housewife to lift or move about the operating parts of the power mechanism.

45 A further object of the invention is to so constitute a dishwasher of the character described that it may be associated with a conventional sink or with a sink of such lines that, to the casual observer, the sink will appear as conventional, when the washer casing is removed.

Another object of the invention is to associate with a washer of the character described power driven scouring, wiping, buffing, or grinding means to assist in the cleaning of pots, pans, 55 cutlery, silverware, dishes, crystalware, etc., in

order to facilitate the proper care of these articles, materially improve their appearance and maintain them free from rust, corrosion and other foreign matter.

A further object of the invention is to provide 5 a novel manner and means for effecting the propulsion of water forcibly upon articles to be washed, through the employment of relatively simple mechanism utilizing a minimum amount of power. The novel manner herein disclosed 10 comprises displacing the surface strata of a body of water by one or more rapidly moving surfaces placed in inclined relation to said surface and preferably projecting both above and below the same and also preferably rotating about an axis 15 normal to said surface.

A further object of the invention is to provide 20 a structure which may be easily maintained in clean and sterile condition and another object is the provision of means whereby clean water may be fed, either continuously or intermittently, into the washer, while the excess water therein is permitted to pass out through an appropriate overflow, for the purpose of maintaining 25 the water in substantially clean condition.

In practically carrying out the present invention I permanently associate with the sink a suitably driven power take-off adapted to project into an accessible position within the confines 30 of the sink and driven from any appropriate source of power. The washer, proper, is in the form of a casing, provided with means for properly agitating water adapted to be contained therein to the end that said water may be thrown upon the dishes or other articles placed in the 35 washer casing for the purpose of cleansing the same. The water agitating means is provided with an operating part which is adapted to be brought into cooperation with the power take-off when the casing is placed in proper position 40 in the sink, so that these parts may be connected together for operation from the prime mover and the articles in the casing washed in a simple and efficient way and without manual exertion. Associated with the sink are one or more 45 spindles with which buffers, scourers, polishers, etc., may be selectively associated and these spindles are driven from the prime mover which constitutes a common source of power for all of the movable operating parts of the structure.

50 Features of the invention, other than those adverted to, will be apparent from the herein-after detailed description and claim, when read in conjunction with the accompanying drawings.

55 The accompanying drawings illustrate different

practical embodiments of the invention, but the constructions therein shown are to be understood as illustrative, only, and not as defining the limits of the invention.

5 Figure 1 is a section on the line 2—2 of Figure 2 and shows a sink in front to rear section and operating parts associated therewith in accordance with the present invention.

10 Figure 2 is a section on the line 2—2 of Figure 1.

Figures 3, 4 and 5 are views similar to Figure 1 but showing modified forms of the invention.

15 Figure 6 is a section similar to Figure 2, but showing another modified form of the invention.

15 Figures 7 and 8 are views illustrating the method of this invention.

Figures 9, 10 and 11 show further modified forms of apparatus embodying this invention.

20 Referring first to the showing of Figures 1 and 2, 1 designates a sink provided with an integral back panel 2 which may conveniently be cast therewith, the sink being provided with a trapped drain 3 and conventional valved water supply faucet 4.

25 The washer casing is indicated generally at 5 and is provided with a cover 6 and appropriate feet 7 which may be conveniently made of rubber or other material which will not scratch a porcelain sink. The casing is of a size and shape 30 to be received into the sink and to rest upon the bottom thereof, as shown in these figures. The interior of the washer casing may be made in various ways, several of which will be hereinafter described as illustrative forms, but, in any event, 35 water agitating mechanism is enclosed therein and is adapted to be driven from a power intake, shown generally in Figures 1 and 2 as a stub shaft 8, projecting through the bottom of the casing 5 and formed to provide a driving connection with the power shaft associated with the 40 sink.

In the embodiment of the invention illustrated in Figures 1 and 2, the power shaft is designated 9. It passes through a water-tight packing or 45 gland 10 in a chambered boss 11 formed at the bottom of the sink and provided therein with a chamber 12 adapted, when the washer is not in use to be closed by a plate 13 flush with the bottom of the sink. The power shaft 9 constitutes the driving shaft, while the stub shaft 8 constitutes the driven shaft. As shown, the former has a polygonal end adapted to be received in a correspondingly shaped socket in the lower end of the latter.

55 On the outboard end of the driving shaft 9 is a worm wheel 14 in mesh with a worm 15 fixed on the armature shaft 16 of an electric motor 17, which constitutes the prime mover or source of power. The worm wheel 14 and worm 60 15 are enclosed within a grease tight casing and are adapted to run in grease, so as to be properly lubricated to run quietly. The motor 17 is supported on a bracket 18 cast integral with or secured to the sink and this motor serves to operate the driving shaft 9 through the worm and worm wheel connection, of such ratio as to impart the desired speed to the driving shaft 9. The motor 17 may be a variable speed motor, but, in practice, I do not find this necessary. It 65 may be controlled from a suitable switch either with or without a rheostat depending upon conditions of the installation.

In the upper portion of the back panel 2 a shaft 19 is journaled for rotation. The rear end 70 75 of the shaft is driven from the tail end of the

armature shaft 16 through any appropriate connections, shown in these figures as a belt and pulley drive, the belt being indicated at 20 and the pulleys at 21 and 22. The forward end of the shaft 19 is threaded to receive a hub of any one of several devices useful in connection with the work to be performed. For example, a buffer 23 is shown as mounted on the shaft 19 in the figures in question, although I may use in lieu thereof any other polishing, cleaning, or scouring device appropriate to the purpose at hand.

The structure shown in Figure 3 is similar, in many respects, to the structures of Figures 1 and 2, but in Figure 3, there is a direct drive between the motor 24 and the driven shaft 8. 15 In other words, the armature shaft 25 of the motor has a squared end which is received directly into the squared socket in the outboard end of the driven shaft. The shaft 25 operates through a gland or stuffing box as before, but the motor is supported on hangers 26 from the bottom of the sink. The tail end of the armature shaft carries a pulley 27 having a belt connection 28 with a pulley 29 mounted on an upright shaft 30 which is journalled at its upper end in 25 the rearwardly extending flange of the back panel 2 and carries a beveled gear 31 meshing with a beveled gear 32 on a countershaft or spindle 33. The shaft 33 is adapted to support one or more polishing, scouring or drying devices and is 30 mounted on suitable bearings on the panel 2. These bearings may be conveniently formed in the opposite ends of a hood or guard 34 which protects the wall back of the sink from particles which may, in practice, be thrown off from the 35 buffer 23.

The motor used in conjunction with this structure is preferably a variable speed motor as this is best suited for the direct drive shown.

In both of the foregoing constructions, the 40 driven shaft extends from the casing 5 centrally through the bottom thereof. In Figure 4, however, the driven shaft 35 projects from one side of the casing 5 and is adapted to cooperate with the driving shaft extending through one of the 45 side walls of the sink. The driving shaft is shown at 36, passes through a water-tight bushing or gland 37 in the back wall of the sink near its base, although it may pass through any other upright wall, and carries a worm wheel 38 50 and a pulley 39. The worm wheel 38 meshes with the worm on the armature shaft 40 of the motor 41, shown as fastened to the wall back of the sink. With the pulley 39 cooperates a belt 42 driving a pulley 43 on the buffer shaft 19. 55

Figure 5 shows a further modification similar to the structure of Figure 4 in that the driven shaft 55 extends through the back of the washer casing 5, while the driving shaft 56 is the armature shaft of the motor 57, so that in this 60 arrangement, there is a direct drive. The motor is mounted on a bracket 58 cast integral with or attached to the sink and the armature shaft carries a pulley 59 which drives the buffer spindle pulley 60 through a belt 61.

In the structure of Figure 6, the driven shaft 44 is positioned off center of the casing 5 and has a squared end received in a socket in the inboard end of the driving shaft 45. A gland or packing 46 precludes leakage through the opening thus necessitated. The outboard end of the driving shaft carries a beveled gear 47 meshing with a beveled gear 48 fixed on the armature shaft 49 of the motor 50. A pulley or sprocket 70 75 is also fixed on this shaft 49 and a belt or sprocket 75

et chain 51 extends around buffer spindles 52 of which one or more may be used. Two buffers 23 are shown of different size and they are shielded by a guard 53 attached to the back panel 2. The drain board of the sink is indicated at 54.

5 By mounting the driven shaft 44 off center a relatively large casing may be used in a relatively small sink which has a drain 3 centrally located, whereas, when the driven shaft is centrally located, the drain 3 should be positioned 10 at one end of the sink as shown in Figure 2.

It will appear from the foregoing description 15 of the several illustrative forms of drive shown, that the drive may vary within relatively wide limits, but, in every case, there is a power shaft 20 permanently associated with the sink and constituting a power take-off with which the driven shaft, forming a permanent part of the washer, is adapted to be detachably associated. I believe this to be broadly novel in that the casing 5, and its directly associated parts, may be 25 readily moved into and out of cooperative relation with the power take-off to be driven thereby or to be removed therefrom and stored away in a convenient place.

The washer casing may, in accordance with the present invention, also vary widely in construction and this is true also of the operating mechanism contained therein. However, I have shown 30 in the drawings illustrative forms embodying this invention.

Generally speaking, the casing may conveniently be made, by casting, spinning or otherwise fabricating the same, into appropriate form and 35 size to receive therein a wire basket 62 which may, if desired, be provided interiorly with partitions or racks, so as to support dishes, glassware, etc. in upright condition. The wire basket may have a suitable handle whereby it may be 40 readily placed into or removed from the casing and when in place therein is adapted to be supported upon a grid or openwork partition 63 which spaces the basket from the bottom of the casing.

45 Into the space or chamber 64 beneath the partition 63, the driven shaft 8 extends and fixed thereon are one or more impeller vanes 65. Figure 3 clearly shows this construction. The vanes extend in a radial direction and are inclined with 50 respect to their plane of symmetry. They may be made of a wide variety of shapes so long as they are satisfactory for the carrying out of the method which I will next explain.

For a clear understanding of this method, attention is directed to Figures 7 and 8 of the drawings. The chamber 64 is adapted to be charged 55 with water up to the level indicated at 66 and the casing 5 may be perforated as shown at 67 to provide an overflow to control this water level, whereby it may be maintained substantially constant. The driven shaft 8 extends through the bottom of the chamber in a direction normal to the water level 66 and the impeller, with its vanes 65, is fixed on this shaft at such a height that 60 the upper edges of the vanes will extend above the surface, while the lower edges of the vanes will be submerged when the vanes are at rest. The vanes are shown as twisted in opposite directions and are adapted to be rotated, so that the upper edges are their leading edges. In practice, 65 they are preferably curved in a longitudinal direction, although they may be straight without departing from this invention and, instead of 70 being flat as shown in Figure 8, they may be 75

curved on their under sides, so as to have a scoop effect.

I have found that when a vane, mounted in this relation to a body of water, is rotated, the phenomena shown in Figure 8 will result and will 5 cause the water to be thrown in an upward inclined direction against the dishes in the basket 62 and against the side of the casing 5 to rebound therefrom as shown. The water will be thrown with considerable force depending upon 10 the speed of the vanes and will produce a highly efficient cleaning of the dishes contained in the basket.

An important feature of this method is that a considerable mass of water is thrown and it is 15 not broken up too finely. As a matter of fact a fine spray will not clean dishes as well as large masses of water thrown in not too finely divided state. Efficient washing of dishes requires mass and velocity and when water is impelled against 20 them in the manner stated, the result is highly satisfactory. The impeller described impels the water in appreciable masses forcibly against the surface of the dishes and effectually cleans them. The fact that the impeller operates at the 25 surface of a pool makes the movement of such a large mass of water possible. The water thrown from the pool against the dishes immediately returns to the pool by gravity to keep said pool at a substantially constant level.

If desired, the overflow 67 may be provided 30 with a cock so that it may be sealed if the washing is to be carried out with a single charge of water, but if the overflow 67 is open or its outflow controlled, fresh water may be constantly 35 fed into the casing, so as to maintain a substantially clean condition of the water therein. This latter result may be efficiently carried out by providing a readily removable connection 68 between the faucet 4 and an inlet nipple 70 on the 40 cover 6, as shown in Figure 1, the faucets being turned on to supply water, either hot or cold, or a mixture thereof, as may be desired, and in such quantities as to maintain the level in the 45 pool and to thereby assist in carrying off impurities and tending to maintain the water in the 50 pool practically clean and at the desired level through a supply of fresh water which may be fed either constantly or intermittently into the casing.

A cage 71 may be supplied in the cover and soap or other detergent material may be housed in this cage to supply the desired suds or soften the water as may be required.

Figure 3 shows a simple form of driving mechanism of the washer for here the drive is direct. In Figure 4, however, where a change in direction of the drive is necessary, the worm wheel 72 is mounted on the impeller shaft 73 and meshes with a worm 74 mounted on the driven shaft 35. 60 The worm and worm wheel are housed within a false bottom 75 mounted on the bottom of the casing 5 and preferably constituting a watertight compartment. The structure of Figure 5 is the same with respect to the worm and gear 65 drive as that shown in Figure 4.

In Figure 6 the impeller shaft 76 has affixed thereto a pulley 77 having a belt connection 78 with a pulley 79 fixed on the driven shaft 44, both pulleys and the belt being housed in a water- 70 proof compartment within the false bottom 75.

Other forms of driving connections between the impeller and the driven shaft may be employed and in some cases a flexible shaft may be used to advantage. The invention is not lim- 75

ited in this connection. In all of the several illustrative forms of the invention which I have described, the arrangement is such, however, that when the washer casing is removed from the sink, the sink may be used in the usual way.

In such forms of the invention as shown in Figures 1, 2, 3 and 6, the opening at the bottom of the sink through which the power is fed may be normally closed by an appropriate plate or cover which may be set into the bottom of the sink flush with the surface thereof, so that to casual appearance, the sink is conventional. In such structures as Figures 4 and 5, where the power outlet is at the upright walls of the sink, the opening through which the power is taken may also be normally closed by a plate and, in the preferred form of the invention, I provide, directly above such openings, pivoted disks 80 which normally gravitate into a position to close these openings. All of the openings, are, however, provided with bushings or packings about the power shafts, so that they will not leak and the covers simply serve to conceal these openings when not in use.

When the dish washer is to be used as such, it is lifted into the sink and its driven shaft brought into engagement with the driving shaft and the parts are thus coupled together for operation. If desired, a locked coupling or a suitable fixture, or both, may be employed to fasten the casing rigidly in position in the sink to preclude the withdrawal of the driven shaft from the driving shaft, but I do not find this necessary as the weight of the casing and associated parts is sufficient to hold the parts in assembled relation. The device is used by charging the casing with water to provide the required pool in the chamber 64. Dishes are thereupon placed in the wire basket 62 and the basket is set in the casing 5 and the cover 6 applied. Power is then turned on to energize the motor and the impeller is driven through any of the forms of the connections described to throw water on to the dishes as shown in Figure 8.

During the operation of the washer, the overflow 67 may be left open and the faucet turned on to supply fresh water continuously or periodically through the connection 68, which conveniently may be a slip hose connection. The casing and dishes remain stationary, the primary moving part being the water impeller which throws the water on to the dishes in appreciable masses to properly cleanse the same.

After the impeller has been operated through a sufficient period to accomplish this result, the motor is turned off, the cover removed and the wire basket may thereupon be lifted out of the casing and set aside temporarily while another wire basket with dishes or other articles therein is placed in the casing for washing while the contents of the previous basket are being dried. If dried through the use of the buffer, a dual result is secured with a single effort for while one load of dishes or articles are being washed, previously washed articles may be dried simultaneously. If desired, the dishes may be dried by holding them against the buffer. Buffers of appropriate shape and size may be used in this connection to dry and polish plates, cups, glassware, cutlery, cooking utensils, etc. These buffers may be employed to clean pots, pans, and other cooking utensils and for sufficiently drying, scouring, polishing or otherwise acting upon and maintaining articles used about the kitchen.

In practically carrying out this invention, the power mechanism may be built into the sink as shown, for example, in Figures 1-3, or it may be incorporated into a conventional sink by simply drilling a hole through the wall of the sink and mounting therein a bearing for the power shaft, the motor being mounted on the wall back of the sink or on the floor. The present invention is not limited in this connection. In the employment of the present invention, the washer and polishing units may be used simultaneously or each may be used separately or either unit may be installed as a separate mechanism.

Figures 9, 10 and 11 show further modified forms of the invention. In Figure 9 the washing casing 5 is shown as provided in its bottom with an impeller 65 mounted on a shaft 81 journaled for rotation on a vertical axis and extending upwardly from the impeller through the confines of the casing 5 and to a point above the same. A fixed sleeve 82 around the shaft precludes the contact of dishes therewith. The casing 5 has a cover 83 provided at its top with a boss 84 through which the shaft 81 extends and the upper end of the shaft is squared at 85 to receive a socketed end of a flexible shaft 86. The flexible shaft is driven from any suitable prime mover such as a motor 87 supported on the sink, wall or on any other suitable firm support. The connection between the flexible shaft and the shaft 81 is a slip connection, so that the flexible shaft may be readily connected to or disconnected from the shaft 81 to allow of the removal and replacement of the cover. The dishes are adapted to be contained in the casing 5 in a wire basket as hereinbefore described which can be readily lifted out when desired.

In the construction of Figure 10, the casing 5 is provided therein with an impeller 65 and an upstanding operating shaft 88, corresponding to the shaft 81 in the preceding figure, and the upper end of this shaft 88 is squared as at 89. Mesh sleeve 82 surrounds shaft 88. The cover 90 is formed therein with a chamber in which is supported a pair of cooperating meshing bevel gears 91 and 92, the former of which has a socket to receive the squared end of the shaft 88 and the latter is secured to a shaft 93 adapted to be detachably associated with the power shaft 94 of a motor 95 permanently associated with the sink. To hold the cover in place, said cover is preferably provided at one side with one or more rigid hooks 96 and at the other side with one or more pivoted hooks 97 which may be engaged with or disengaged from the bead at the top of the casing 5 to lock the cover in place. When the hooks 97 are released the cover may be lifted from the casing, carrying with it the gears 90 and 91 and the shaft 93 and disengaging the gear 91 from the upper end of the shaft 88. The dishes or other articles are adapted to be received within the casing 5 in an appropriate wire basket as before.

In the structure of Figure 11, the impeller 65 is fixed on a shaft 98 carrying a bevel gear 99 which is driven by a bevel gear 100, fixed on a shaft 101. This shaft carries a bevel gear 102 exteriorly of the casing and with this bevel gear meshes a second bevel gear 103 fixed on an upright shaft 104. The upper end of shaft 104 is squared at 105 to fit the socket of any appropriate driving connection, such, for example, as a flexible shaft of the character shown in Figure 9, driven from a motor or any other suitable source of power. The greater portion of the

length of the shaft 104, as well as the bevel gears 102 and 103 are housed within a casing 106 of any appropriate kind.

In the foregoing detailed description of the several forms of the invention which I have chosen to show by way of illustration, the power take-off or power shaft is driven from an electric motor. I may, however, employ any other appropriate prime mover for the power shaft and this prime mover may be mechanical, electrical or otherwise and it may constitute, if desired, a crank or treadle adapted to be manually operated. The main consideration is that a shaft is provided from which power may be taken off to drive the operating parts of the washer in the manner hereinbefore described.

In the drawings I have shown the prime mover as mounted in various places. In some instances, it is supported directly on the sink. In other instances it is supported on the wall back of the sink. I wish it understood in this connection that the prime mover may be mounted anywhere desired and may be mounted on the floor or on a bracket or pedestal on the floor or in any other desirable and suitable location or place that may be convenient for any particular installation.

In the carrying out of the method of this invention very good results have been obtained where the vanes are rotated so as to be partially submerged in the water in the container. I do not wish to limit this partial submerging to any particular degree and in some cases the vanes may be submerged entirely but closely adjacent to the surface of the water, as the fundamental purpose of these vanes is to agitate and throw the water as described and I do not limit to more or less submersion so long as the effect described in connection with this method is carried out.

It will be noted from Figure 11 that I have shown a water draw-off at the base of the casing 5 and this draw-off may be associated with the casings of any of the other forms of the invention shown. In any event it is located so as to drain the pool from the casing when desired. It may be of any appropriate form, but is shown as a screw plug 107 attached by a chain 108 to the casing, so that when it is removed it cannot be lost. To drain the water from the pool the plug may be removed and the water will run out.

After the water has been drained as stated, the washed dishes contained within the casing may be completely or partially dried by operating the impeller as a fan, so as to produce a draft of air through the dishes in the casing. The motors shown in the several figures may be of the reversible, variable speed type, with appropriate controls as will be well understood in the art, so that the impeller may be used as a fan to force air through the dishes to dry or partially dry the same. It will be understood of course in this connection that the cover should be removed while this operation is carried out and most of the figures of the drawings are so constituted as to permit of the operation of the fan with the cover removed. However, in such structures as Figure 10, the cover may be provided with an appropriate opening having a suitable closure which may be removed to permit of the passage of air into and out of the casing to be acted upon by the fan for the purpose stated.

The fan may be operated for a sufficient period to thoroughly dry the articles in the casing or it may be operated long enough to effect a partial drying of the same and in any event the

articles may be subsequently removed from the casing in dried or partially dried condition and the drying or polishing completed by use of the buffers or other drying or polishing devices to which I have referred.

In Figures 9, 10 and 11 I have not shown polishing, drying or buffing units, but it will be understood that such units may be associated with these constructions in any of the ways hereinbefore described or in any suitable or equivalent manner. E. g., I may, if desired, so position the driving motors that their shafts extend from opposite ends of the motor casings with the driving connections for the washer coupled to one end of the shaft, and a polishing, drying or buffing unit mounted on the other end of the shaft.

I have shown in the several figures of the drawings different modified forms of driving connections between the prime mover and the impeller, but I wish it understood that I may use such appropriate driving connections as may be desired and these connections may embody either belts, gears, flexible shafts or a combination of one or more of these forms of connection for the transmission of power.

I have hereinbefore referred to the power operated shaft which extends into the sink, as mounted on the sink or on the brackets or otherwise associated therewith, but, if desired, this power operated shaft may be supported on the wall or on a bracket on the wall, or on any other suitable support and not necessarily on the sink itself, so long as it projects into position to properly cooperate with the operating mechanism of the washer casing.

In the several figures of the drawings and in the description of these individual figures, I have shown and described different features of the invention, but in the interests of simplicity of disclosure, I have not attempted to apply all of these features to each and every construction. It is to be understood, however, that in practically carrying out the invention in any of its forms, I may use in any particular form or forms any of the features described in any one or more of the other forms. E. g., it should be borne in mind that the water supply, drain, overflow, use of drying air and kindred features described in conjunction with particular features is applicable to all of them.

This invention should not be confused with those suggested prior art devices wherein some part of the sink enters into or constitutes a housing for the operating parts of a washing machine. Such prior devices are characterized by the fact that special sinks provide for the assembly of washing apparatus therein and which washing apparatus employs a part of the sink to house some part of the washing apparatus. The present invention is wholly distinct and different from these suggested prior devices in that, among other important features, it embodies a complete and self contained dishwashing machine which comprises a casing including all of the dishwashing operating parts and adapted to be picked up bodily and placed into or out of the sink. The casing is an inherent part of a complete operating dishwashing mechanism and does not depend for the housing of any of these operating parts upon any part of the sink. All that the sink carries is a power shaft to which the otherwise complete and self contained dishwashing machine is adapted to be coupled when it is placed in a sink.

In the foregoing detailed description I have set

forth different practical forms of the invention for the purpose of illustration, but the invention is to be understood as fully commensurate with the appended claim.

5 This application is a division of my co-pending application, Serial No. 119,775, filed January 9, 1937.

Having thus fully described the invention, what I claim as new and desire to secure by Letters

10 Patent is:

In an assembly of the character described, a sink comprising a basin having a substantially flat bottom, and upstanding walls at the front, sides and back thereof, a power shaft projecting

into accessible position within the confines of said basin, a separate complete dishwasher casing of greater depth than the depth of the basin, removably seated within said basin and projecting above the front and side walls thereof and extending appreciably above the confines of the basin, complete dishwashing means housed within said casing including a driving shaft accessible from the exterior of the casing, and means detachably connecting the driving shaft of the 5 casing to the power shaft of the basin to operate the washing means within the casing from said power shaft.

CLEMENT EHRET.
